ELECTRICAL SWITCH

Graham D. Bogel, 240 Rosemont, Webster Groves, Mo.
Filed Oct. 28, 1963, Ser. No. 319,138
16 Claims. (Cl. 340—37)

The invention relates to electric switches and consists particularly in a switch adapted to receive several continuously variable inputs and provide a continuously variable output which is a mathematical function of the inputs.

The art of control has advanced substantially in recent years. It is presently the practice to provide continuously varying inputs to many devices. Present practice requires rather extensive circuitry or mechanical conversion means to provide both high current capacity and variable outputs at the same time. Such devices produce objectionable mechanical and electrical noise and are subject to considerable wear. Because of their complexity they are frequently difficult to understand and service.

Accordingly it is a main object of the invention to provide a switching system that will respond to several variable inputs (either digital or analog), and provide a variable output which is mathematical function of the switching geometry.

A further object is to provide a switching system capable of operation with a minimum of noise and wear.

It is an additional object to provide a functionally sophisticated control device of such structural simplicity that it may be easily understood and serviced.

The foregoing and additional more detailed objects and advantages are attained by the structures described hereinafter and illustrated in the accompanying drawings, in which:

FIG. 1 is a transverse vertical sectional view of a switch embodying the invention.

FIG. 2 is a top view of the switch illustrated in FIG. 1, taken along line 2—2 of FIG. 1.

FIG. 3 is a fragmentary horizontal sectional view along line 3—3 of FIG. 1.

FIG. 4 is a transverse vertical sectional view taken along line 4—4 of FIG. 5, illustrating a modified form of the invention.

FIG. 5 is a view of the switching element shown in FIG. 4.

FIG. 6 is a schematic circuit diagram showing the connection of the switch illustrated in FIGS. 4 and 5 to highway traffic signals.

FIG. 7 is a transverse vertical sectional view of a third form of the switch embodying the invention.

In the embodiment illustrated in FIGS. 1—3, the switch is arranged to provide percentage timing of a high mass heat source S. The contact means of the switch is a liquid ball 3 preferably of mercury or mercury alloys, although it may be of some other conducting liquid with sufficient relative surface tension to hold itself together in contact with the switching elements and not separate into smaller balls.

The switch comprises a shallow pan 1 of metal, the inner surface of which is the surface of revolution of a mathematical curve selected to give a useful displacement of the ball 3 proportional to the angular displacement of the pan.

Pan 1 is universally tiltably mounted on a needle type pivot 5 and is stabilized thereon by bellows 7, pivot 5 being selectively vertically movable for the purpose of introducing a variable input to the switch. The pan is nonrotatable in the horizontal plane.

The mercury receiving bottom of pan 1 is sealed by an insulating plate 9 in order to protect the mercury from dirt and foreign substances and to permit the cavity to

2

be filled with a suitable inert gas if desired. Within the cavity also, and spaced from the bottom of the pan, is a switching element 11 of multifoil shape in plan, although the specific shape is a matter of choice depending upon the function of the switch, the spacing of switching element 11 from the bottom of the pan being sufficient to permit contact therewith of the conducting liquid ball 3. Switching element 11 is supported from insulating plate 9 by a plurality of posts 13 and a conducting post 15 which protrudes upwardly through the insulating plate. Mass heat source S is connected to a suitable source of power by leads 17 and 19, lead 17 being directly connected to the heat source and lead 19 being connected to terminal 21 on switch pan 1. The other power input lead 21 of heat source S is connected to terminal post 15 of switching element 11, so that as long as ball 3 is in engagement with the inner surface of pan 1 and a surface of switching element 11, current will pass to the heat source, energizing the same. The ball can be moved, however, by tilting pan 1 and may be made to rotate or follow any desired path by causing the pan to wobble or precess. The latter type of movement is provided by a rotating arm 23 on the end of which is mounted a double flanged roller 25 of insulating material such as nylon, the groove of the roller being engageable with the upper rim 27 of pan 1. Arm 23 is pivotally mounted at 29 transversely of upright shaft 31 of motor 33 and extends therebeyond and upwardly to a connection at 35 with bimetal thermostat 37 on heat source S, the thermostat 37 being rotatably mounted on the heat source to permit it to rotate with arm 23 as the latter is rotated by motor 33. With motor 33 in operation, and with arm 23 horizontally disposed as shown in FIG. 1, as arm 23 rotates, no movement will be imparted to pan 1 and conducting liquid ball 3 will remain in the position shown in FIG. 1. However, as the temperature of heat source S increases, the outer end of bimetal thermostat 37 will move upwardly, causing a corresponding downward movement of the outer roller-mounting end of arm 23 and this will cause pan 1 to wobble about its pivotal support 5, thereby causing mercury ball 3 to move outwardly to a position such as that shown in FIG. 3 and to rotate along a circular path such as that shown in broken lines in FIG. 3. As ball 3 follows this path it will only be in intermittent contact with element 11 throughout its travel and the mass heat source circuit will be made and broken accordingly. Should the heat source continue to rise in temperature, thermostat 37 acting through arm 23 would tilt pan 1 until ball 3 was further from the center than the outer ends of the foils of element 11, thereby completely cutting off the supply of current to the heat source until the heat source and thermostat cooled down to permit a reduction in the tilt of arm 23 sufficient to bring the path of ball 3 into engagement with switching element 11.

Although, for some purposes, motor 33 might be operated at constant speed and pivot member 5 maintained at constant height so that the only variable input would be the movement of arm 23 caused by the effect of temperature changes on bimetal thermostat 37, it would be possible to continually vary the motor speed and also to vary the height of pivot member 5, either manually or by mechanical means so that the movement of the ball and the making and breaking of the circuit would be a function not only of the upward and downward movement of arm 23, but also of the upward and downward movement of pivot member 5 and variations in motor speed.

Operation of this form of the device is as follows: With heat source S cold, the pan would be in the position shown in FIG. 1 with the liquid ball centered and engaging the central portion of the quatrefoil switch element 11. As the heat source warms up, the outer end of

thermostat 37 moves upwardly, gradually causing downward movement of the outer end of arm 23 and outward movement of ball 3 on its generally circular path. Initially the ball will be in constant contact with element 11 but as the thermostat warms up and the outer end of arm 23 moves downwardly causing greater tilting and wobbling of pan 1, the spacing of the ball from the center of the pan increases and in its path it is out of contact with switch element 11 throughout a greater part of its circuit, only making contact when it is beneath the leaves of the multifoil element. During the periods when the ball is not in contact with the multifoil element, the circuit through the heat source is broken. If the heat source continues to heat up beyond a predetermined value, the thermostat, acting through arm 23, causes the pan to tilt so far that the path of the ball is entirely outwardly of switch element 11, thereby cutting off power to the heating source until it cools down.

The embodiment of the invention shown in FIGS. 4-6 is arranged to control traffic lights between a main and a secondary road. In this embodiment of the invention, arm 23 is operated by a traffic counter C on the secondary road, and the switching element consists of a curved plate 39 supported from insulating plate 9 and a peripheral ring 41 surrounding and slightly spaced from element 39. Plate 39 is separated into a plurality of sections 43, 45, 47 and 49 insulated from each other and each supported from insulating plate 9 by one or more posts 44, 46, 48 and 50, respectively.

Referring to FIG. 6, a pair of traffic signals 51 for a main road and 53 for a secondary road are shown. Each of the signal indication lights R, A and G is connected by a line 55 and branch lines 57, 59, 61 to a source of electric power, and the other power line 63 is connected directly to terminal screw 21 on pan 1. Segment 43 of element 39 is connected by line 65 to the red light on secondary road signal 53 and therefrom by means of line 67 to the green light on main road signal 51 so that when the mercury ball is under segment 43, the secondary road signal will be red and the main road signal, green. Segments 45 and 49 are connected by line 69 to the amber light on the secondary road and therethrough by means of line 71 to the amber light on the primary road signal 51 so that when the mercury ball is in either of these segments, both amber lights will be illuminated.

Segment 47 is connected by means of line 73 to the green light on secondary road signal 53 and is connected therethrough by means of line 75 to the red light in main road signal 51 so that when the mercury ball underlies segment 47 the green light on the secondary road signal 53 will be exhibited and the red light will be exhibited on the main road signal 51. Peripheral ring 41 is connected by line 77 to the armature 79 of a flasher relay 81, the other contact 83 of which is connected by a line 85 to the amber light of the secondary signal 53 so that when the ball is in engagement with ring 41 there will be a flashing amber indication on both road signals. Normally, in the absence of traffic on the secondary road, arm 23 would be tilted by traffic counter C so that ball 3 would be in engagement with ring 41, i.e., at its outermost position, and motor 33, rotating at constant speed, would maintain ball 3 in contact with ring 41 thereby making a circuit through flasher relay 81 and causing amber lights to flash on both road signals 51 and 53. This rotation would terminate at point 87 due to the engagement of arm 23 with fixed stop element 86 depending from the housing of motor 33. As soon, however, as traffic occurs on the secondary road, traffic counter C causes arm 23 to move upwardly at its outer end and correspondingly downward at its short end, clearing the lower end of stop element 86, also reducing the tilting of pan 1 and causing inward movement of liquid ball 3 into engagement with segment 43 of switch element 39. Then, as will be evident from circuit schematic diagram of FIG. 6, through lines 65 and 67, the red

light of secondary road signal 53 will be illuminated and the green light of main road signal 51 will be energized. As arm 23 rotates ball 3 will move into segment 45, and through lines 69 and 71 will energize both of the amber signals, after which the ball will move into engagement with segment 47 thereby, through line 73, energizing the green light of secondary road signal 53 and, through line 75, the red light of main road signal 51, after which the ball will pass into engagement with segment 49 by means of which, through lines 69 and 71, it will energize both of the amber lights, thence back into engagement with segment 43 with energization of the secondary road red light and main road green light. As traffic increases on the secondary road, the outer end of arm 23 will be raised, thereby reducing the tilting of pan 1 and moving the ball ever closer to the center of the pan, thus reducing the linear travel of the ball through the segments and speeding up the cycle of the signal. The segments of course can be of any suitable size, segment 43, the green light segment for the main road and red light of the secondary road, being of maximum size, and the segments 45 and 49, amber segments for both roads, being of equal size, and segment 47, the green light segment for the secondary and red light for the primary road, being substantially smaller than segment 43.

For providing an all-red indication when desired, the red lights of both signals 51 and 53 have lines 89 and 91 extending through insulator 9 and through a central aperture 93 in switch element plate 39. By manually lowering pivot support element 5 until pan 1 is horizontal, as shown in FIG. 4, ball 3 may be brought into contact with leads 89 and 91 causing an all-red indication and permitting manual traffic direction in emergencies.

Operation of the form of the invention illustrated in FIGS. 4-6 is as follows:

In the absence of traffic on the secondary road, counter C maintains arm 23 and pan 1 tilted, so that liquid ball 3 is in engagement with ring 41 thereby, through flasher relay contact arm 79 and lines 85 and 71, intermittently energizing the amber lights in main road signal 51 and secondary road signal 53. Irrespective of where arm 23 was originally rotationally positioned, it will be rotated by motor 33 until its short end engages stop 86 so that roller 25 will engage the rim of pan 1 at point 87 and accordingly that, when traffic occurs on the secondary road, the liquid ball 3 will engage segment 43, causing a green indication on the main road signal and a red indication on the secondary road signal. As the output plunger of the traffic counter C moves upwardly, indicating traffic on the secondary road, the short end of arm 23 is moved downwardly, clearing the lower end of stop 86 to permit the arm to rotate, and the long end correspondingly upwardly, thereby causing the liquid ball to move inwardly, out of engagement with ring 41 and into engagement with segment 43, to cause, through lines 65 and 67, a green indication on main road signal 51 and a red indication on secondary road signal 53. As the motor rotates arm 23, the ball passes successively from segment 43 to segments 45, 47 and 49, causing correspondingly successive illumination of both amber lights, the red light of the primary road signal and the green light of the secondary road signal, both amber lights, and thence back into engagement with segment 43 and illumination of the main road green light and the secondary road red light. As traffic increases on the secondary road, the counter plunger will move further downwardly, causing corresponding upward movement of the outer end of arm 23 and consequent reduction of the tilting of the pan, thus bringing the liquid ball closer to the center of the pan and reducing the linear distance of its travel per cycle, and correspondingly speeding up the cycle. If an all-red indication on both signals is desired, the pan can be lowered, by manually lowering support 5 until the pan is level; when this occurs ball 3 will be out of engagement with plate 39 and close the circuit including both red lights and lines 89 and 91. By

raising the pan to its normal height, normal automatic operation of the signals can be restored.

In the embodiment of the invention illustrated in FIG. 7, the switch includes a continuously variable radio frequency transformer, having helical primary and secondary coils 92 and 93 supported in vertically spaced relation from each other and the inner surface of pan 95 which is made of insulating material and is supported only on bellows 96. This switch is arranged to short out varying numbers of the secondary coils and accordingly the pan is provided with a hemispherical sump 97 at its center filled with a quantity of mercury or other conducting liquid 99, so that when the pan is tilted, the liquid will be disposed in a long stream extending radially outwardly from the center of the pan. The length of the stream of liquid and the number of turns shorted out will depend on the degree to which the pan is tilted, which, of course, will be a function of the input variables introduced by tilting arm 23 and by raising or lowering the pan by the introduction into or removal of fluid from bellows 96.

Operation of this form of the invention is as follows: The primary coil 92 is energized, and, if the pan is horizontal, all turns of the secondary coil will function to provide the maximum output voltage. If the input on arm 23 is varied, or if the height of the pan is varied by bellows 96, the pan will tilt, causing the fluid in sump 99 to stream radially outwardly therefrom, shorting out some turns of secondary coil 93 and in effect reducing its number of turns and the output voltage. The number of turns shorted out will, of course, vary in accordance with the tilting of the pan, which is a function of the inputs on arm 23 and bellows 96.

It will be understood that, although switches constructed in accordance with my invention may be used for numerous purposes other than those disclosed herein, where several continuously variable inputs and a continuously variable output are required, and such switches may be modified in various respects as will occur to those skilled in the art, the exclusive use of all modifications as come within the scope of the appended claims is contemplated.

What is claimed is:

1. An electrical switch comprising a circular pan, a support for said pan permitting universal tilting movement thereof, an arm mounted on an axis concentric with said pan for rotation relative thereto and engaging the periphery of said pan, said arm being tiltable on an axis normal to its rotatable axis for imparting a wobbling movement in said pan as it rotates, a mass of conductive liquid in said pan movable in accordance with wobbling movements thereof, and conductive surfaces in said pan spaced above the inner surface thereof less than the normal free height of said liquid mass, said surfaces being separated from each other, whereby said conductive surfaces are adapted to be contacted by said liquid mass during movements thereof.

2. An electrical switch according to claim 1 in which said pan is nonrotatable.

3. An electrical switch according to claim 1, including a plate-like element spaced above the inner surface of said pan, said conductive surfaces being portions of the lower surface of said element.

4. An electrical switch according to claim 3, in which portions of said element are cut away to provide discontinuities in its lower surface.

5. An electrical switch according to claim 4 in which said element is of multifoil shape.

6. An electrical switch according to claim 1 in which said pan is arranged for selective movement along its vertical axis.

7. An electrical switch according to claim 1, including means for rotating said arm at selected speeds.

8. The combination with a switch according to claim 1 of a source of electric power, an electrical heat source, the inner surface of said pan and said conductive surfaces forming the controls of said switch, an electrical

conductor connecting said heat source with one of said contacts and the other of said contacts being connected to said power source, and means responsive to changes in temperature of said heat sources and operatively connected to said arm for tilting the latter in accordance with changes in temperature of said heat source.

9. The combination with a switch according to claim 1 of a source of electric power, a pair of traffic signals each having stop, caution, and proceed indications, the inner surface of said pan and said conductive surfaces forming the contacts of said switch, one of said contacts being connected to said power source, the other of said contacts comprising segments insulated from each other and connected respectively to the stop indication of one of said signals and the proceed indication of the other signal, to the caution indications of both signals, and to the proceed indication of said one signal and the stop indication of said other signal, a traffic counter having its output connected to said arm for varying tilting of said arm and of said pan in accordance with traffic conditions and thereby varying the displacement of said liquid mass from the center of the pan and thus varying the length of the signal cycle.

10. The combination according to claim 9, including an additional annular contact surrounding and insulated from said segments, and a conductor connecting said annular contact and said caution indication and including an intermittently opened and closed switch whereby when said liquid mass is in engagement with said annular contact the caution indications of both said signals will be intermittently energized.

11. The combination according to claim 9 in which said segments are spaced from the center of said pan, and including a pair of spaced contacts connected to the top indications for energizing the same when said pan is horizontal and said liquid mass is centered therein and in engagement with both said contacts, and means for selectively varying the height of said pan on its support whereby to position said pan horizontally irrespective of the tilting of said arm.

12. The combination according to claim 10 in which one of said signals governs a main road and the other signal govern a secondary road and said traffic counter is arranged to measure traffic on said secondary road and maintain said arm at its maximum tilted position, with said liquid mass in engagement with said annular contact, in the absence of traffic on the secondary road, and to reduce the tilt of said arm as traffic on said secondary road increases to move said liquid ball inwardly of the pan from said annular contact and into successive contact with said segments as said arm rotates, the linear travel of said liquid mass through a complete cycle being reduced as the tilt of said arm is reduced and said ball approaches the center of the pan.

13. The combination according to claim 12 in which the segments connected respectively to said proceed indication of one said signal and said stop indication of said other signal and to said stop indication of said one signal and said proceed indication of said other signal are spaced apart by the segments connected to the caution indications of both signals.

14. The combination according to claim 13, including means for stopping rotation of said arm when said arm is at its maximum tilt position and overlies the segment connected to the proceed indication of said main road signal and the stop indication of said secondary road signal whereby, when traffic commences on said secondary road and the tilt of the arm is thereby reduced and the liquid mass moves into contact with said segment, thereby causing a proceed indication on the main road signal, and a stop indication on the secondary road signal, said stop means being arranged to release said arm and permit its rotation upon the commencement of traffic on the secondary roads.

15. An electrical switch according to claim 1, including

a helical coil uniformly spaced from the inner surface of the pan, said pan including a sump at its center filled with said conductive liquid, whereby upon tilting of said pan the liquid spills out of said pump in a radial stream contacting adjacent turns of said coil, the number of turns contacted being proportional to the length of the stream and tilt of the pan.

16. An electrical switch according to claim 14, in which there is a second helical coil spaced upwardly from said first named helical coil, said coils forming the primary and secondary of a variable transformer.
